ELECTRICAL UTILITY BRUSH

Samuel Mayer, New York, N. Y.

Application May 17, 1944, Serial No. 535,915

2 Claims. (Cl. 15—23)

1

This invention relates to new and useful improvements in a power driven rotary utility tool for cleaning, polishing, buffing or the like, and more particularly to such a tool adapted to be hand operated.

More specifically, the invention proposes the construction of a rotary tool adapted to be driven by an electric motor forming part of the tool or by a flexible shaft and having two rotatable elements such as two brushes, or two buffers.

Still further it is proposed to provide a tool as aforesaid having a dust bin for collecting dirt picked up by the rotating elements.

A further object of the invention is to provide a small hand size power driven tool adapted to receive rotatable brushes, buffers or other means.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a sectional view of a power driven brushing tool constructed in accordance with this invention, taken on the line 1—1 of Fig. 3, parts being shown in full.

Fig. 2 is a plan view of the tool.

Fig. 3 is a side elevation of the tool.

Fig. 4 is a section on the line 4—4 of Fig. 2.

Fig. 5 is a view similar to Fig. 1 showing a tool constructed in accordance with a modification of this invention.

Fig. 6 is a plan view of a buffer that may be employed with the tools shown in Figs. 1—5.

The tool shown in Figs. 1—4, according to this invention includes a body 10 which consists of a handle 11, a support 12 integral with the handle, a hood 13 extending from the support and a support 14 at the other end of the hood. The body 10 is preferably made of several pieces secured together, as shown. For instance, the handle 11 and support 12 may be made of a single piece of wood. The support 14 may be made of another piece of wood. The hood 13 may be made of thin sheet metal secured to the supports 12 and 14 by screws 15. Other kinds of material may, of course, be employed if desired.

Handle 11 has a central chamber 16 in which is housed a small electric motor 17, which is shown diagrammatically in Fig. 1 and may be a well known type of motor such as is used in small electric hand drills. A bore 18 extends from chamber 16 through support 12 and a bushing 19

2

is disposed in this bore. A plug 20 closes chamber 16 at the other side of motor 17 and has a central bore 21 through which passes an electric cord 22 supplying current to the motor 17. Plug 20 may be removably secured to the handle in any desired manner so that it may be removed when it is desired to service or repair the motor 17. Aligned recesses 23 are formed in each side of supports 12 and 14, and bushings 24 are secured therein.

A dust-collecting bin 25 is secured to the underside of hood 13, as by spot welding. At one end it engages the support 14 and may be secured thereto if desired. At the other end it is spaced from support 12 and is closed by an end wall 26. Bin 25 has opposite side openings 27 and 28 and a bottom wall 29 having an opening 30 closed by a hinged and latched door 31. The interior of the bin is partitioned by a wall 32, formed by folding inward a portion of the top wall of the bin, into two chambers 33 and 34, opening 27 opening into chamber 33 and opening 28 opening into chamber 34. The top edge of opening 27 is curved outwardly forming a deflector 35 and the bottom edge of opening 28 is curved outwardly forming a deflector 36.

A shaft 37 is journaled in bushing 19. Shaft 37 at one end is connected to the armature not shown, of the motor 17 and at the other end a gear 38 is secured to shaft 37. This gear is disposed in the space between the adjacent end of the bin 25 and the support 12. The bin may form means preventing shaft 37 from becoming operatively disassembled from motor 17. A hollow shaft 39 is journaled in each of the bushings 24 and a gear 40 is secured to each of these shafts and meshed with gear 38 to be driven thereby. A brush 41 is disposed on each side of bin 25, each brush having one end disposed inside the adjacent hollow shaft 39 and secured thereto by a set screw 42 and its other end freely disposed in the aligned opposite bushing 24 supported in support 14. The end of the brush disposed in bushing 24 may be rounded in any well known manner, as by building up with weld metal, or it may have a small sleeve forced on it, which sleeve acts as a journal in the bushing 24.

The operation of this form of device is as follows:

50 The electric motor rotates the gear 38 and thereby the gears 40, which rotate the brushes 41. The brushes 41 may be employed for instance, to brush clothing. They rotate in the same direction and as each brush passes its deflector 35 or 55 36, as the case may be, it throws the dirt or dust

it has collected into the bin 25. When the bin is filled, it may be emptied through the door 31. Wall 32 prevents the dust being thrown in the bin from one opening from passing out through the other opening.

The tool described may be used for many purposes such as for brushing clothing, furniture, automobile upholstery and so forth. It has particular adaptation for getting into small places and for being employed as a hand tool facilitating many household tasks. Its operation promotes sanitation in that all dust or dirt removed from an article is collected in the bin and prevented from blowing around where it can be breathed in by the person operating the tool.

When used to brush fabrics, soft brushes may be employed. However, the tool may also be employed with hard brushes for cleaning pots and pans, walls and so forth. It may also be used to shine shoes and for polishing wax. If desired, the brushes may be replaced with buffers such as the buffer 43 shown in Fig. 6. The tool may then be employed for cleaning windows, mirrors, and the like.

The brushes may easily be removed from the tool for cleaning by taking out the screws 15 in support 12 and moving support 14 away from support 12, gears 40 staying with the brushes 41 when they are removed from the tool. If it is desired to replace the brushes, with new brushes or with buffers, they may be removed from the gears 40 by removing the set screws 42.

The invention is applicable to rotary brushes and buffers for employment with water, cleaning fluid or other liquids. In such case, as the liquid might interfere with the electric motor, it is contemplated to employ instead a flexible shaft. Such a construction is shown in Fig. 5 wherein the tool is distinguished from the tool shown in Figs. 1-4 in that the shaft 37' is driven by a flexible shaft 44 which extends through the bushing 19' disposed in the handle 11'. In other respects this tool is similar to the tool of Figs. 1-4.

The brushes 41 of the form of the invention shown in Figs. 1 to 4 or the brushes 41' in the form of the invention shown in Fig. 5 may be replaced, when desired, by rotary buffers, one of which is shown at 43 in Fig. 6. To substitute buffers of the type shown in Fig. 6 for the brushes, the utility tool is disassembled to free the brushes in the manner previously described for freeing the brushes to facilitate cleaning thereof.

While I have illustrated and described the preferred embodiments of my invention, it is to be understood that I do not limit myself to the pre-

cise constructions herein disclosed and the right is reserved to all changes and modifications coming within the scope of the invention as defined in the appended claims.

Having thus described my invention what I claim as new, and desire to secure by United States Letters Patent is:

1. A brush comprising a handle having a recess, driving means disposed in said recess, a hood secured to said handle and open at its bottom, said hood having longitudinally curved sides, two spaced rotatable cylindrical brushes in said hood, one adjacent each of said curved sides, gear means connecting said brushes with said driving means, a dust bin disposed between said brushes, said dust bin having a curved side portion adjacent each of said brushes, each of said curved sides having an opening adjacent its correlated brush and above the bottom of said dust bin, said dust bin further having a bottom wall between said side walls, said bottom wall being provided with an opening, a hinged door for said bottom wall opening, and a partition in said dust bin between said side walls and extending from the top of said dust bin to adjacent said door for preventing dust from blowing out of its side openings, said brushes extending below said hood.
2. A utility brush comprising a handle and a hood portion connected therewith, a pair of spaced parallel brushes mounted for rotation in said hood, a receptacle for collecting dust secured on said hood and disposed intermediate said brushes, said receptacle having a pair of openings formed therein, said openings comprising dust admission ducts to the interior of said receptacle, each of said openings being positioned adjacent one of said brushes, a baffle plate mounted in said receptacle and positioned intermediate said openings, means for removing dust collected in said receptacle comprising an opening formed in said receptacle and a closure member therefor, and driving means connected with said brushes.

SAMUEL MAYER.
